UNITED STATES PATENT OFFICE.

WALTER SOUTHWICK, OF NEW YORK, N. Y.

HEEL FOR RUBBER BOOTS OR SHOES.

SPECIFICATION forming part of Letters Patent No. 301,638, dated July 8, 1884.

Application filed May 9, 1884. (No model.)

To all whom it may concern:

Be it known that I, WALTER SOUTHWICK, of the city, county, and State of New York, have invented certain new and useful Improvements in Heels for Rubber Boots and Shoes, of which the following is a full, clear, and exact description.

My invention relates to that class of heels wherein an outer plate of rubber, leather, wood, or roughened metal, more particularly the latter, is used for protecting the heel and for preventing the wearer from slipping upon the ice; and the invention consists in the construction and arrangement of parts, as will be hereinafter described and claimed.

Reference is to be had to the accompanying drawings, forming a part of this specification, in which similar letters of reference indicate corresponding parts in all the figures.

Figure 1 is a sectional elevation of a rubber boot or shoe having my new and improved heel applied thereto. Fig. 2 is a bottom view of the same, the roughened plate being removed; and Fig. 3 is a plan view of the outer surface of the roughened plate.

In forming my new and improved heel I employ the D-shaped plate A, which I secure to the rubber heel portion B of the boot or shoe C by the rivets a a, which are passed through the countersunk opening b b of the plate A; thence through the heel portion B and bottom c to the inside of the boot or shoe, where they are headed, as shown in Fig. 1. The heel is rabbeted at B', in order that the plate A may be set flush with the face thereof. The D-shaped plate A, besides having the holes b made through it for the passage of the rivets a, has the three screw - openings d (more or less) formed in it, to receive the short screws

e, for holding the plate D securely in place 40 upon the heel. The outer plate, D, is, by preference, made of metal, and corrugated or ribbed to form the sharp teeth or ridges g, so that the plate will serve not only to protect the heel, but also to prevent all danger of the 45 wearer slipping upon the ice.

By the use of the plate A, riveted through the heel, and by screwing the outer plate, D, to the plate A, a very firm and secure attachment of the plate D is effected, and the heel 50 is made by the rivets a very firm and strong, and has a perfectly secure connection with the boot or shoe, so that the heel cannot by any common usage be detached from the bottom or sole of the boot or shoe.

Having thus fully described my invention, I claim as new and desire to secure by Letters Patent—

1. The combination, with the heel B, of the D-shaped plate A, provided with apertures 60 b and screw-threaded apertures d, rivets a, passing through the apertures b and the heel, as shown, the serrated or toothed plate D, secured to the plate A by screws e, engaging the threaded apertures d, substantially as set forth. 6:

2. The combination, with the heel B, rabbeted at B', of the D-shaped plate A, fitting within said rabbeted portion, and provided with apertures b and screw-threaded apertures d, rivets a, passing through apertures b 7' and the heel, and there headed down, and the serrated or toothed plate D, secured to the plate A by screws e, engaging the screw-threaded apertures d, substantially as set forth.

WALTER SOUTHWICK.
